Fig. 3.

Dudley B. Howard, Inventor

UNITED STATES PATENT OFFICE.

DUDLEY B. HOWARD, OF WASHINGTON, DISTRICT OF COLUMBIA.

FLINCH INDICATOR FOR FIREARMS.

Application filed June 3, 1921. Serial No. 474,871.

To all whom it may concern:

Be it known that I, DUDLEY B. HOWARD, a citizen of the United States, residing at Washington, District of Columbia, have invented certain new and useful Improvements in Flinch Indicators for Firearms, of which the following is a specification.

This invention relates to firearm accessories, and in particular to a device for indicating when the firer of a weapon convulsively jerks his piece out of proper firing position at the time of discharge, which is commonly known as "flinching."

Flinching is due to lack of muscular control resulting from nervousness caused, or at least aggravated, by fear of being injured during recoil of the weapon. A man thus affected may start to squeeze the trigger carefully, but will suddenly lose control of himself. He will invariably stop adjusting the aim, "pull" the trigger violently, flex his arms so as to derange the position of the piece, and go through other contortions.

In the military service, flinching is a serious factor to be dealt with in the training of recruits in target firing with small arms, such as the magazine rifle, automatic rifle, and pistol. Heretofore, certain schemes have been tried in an effort to detect and overcome this tendency on the part of gunshy men. One scheme is to insert a "dummy" cartridge in a broken clip of ball cartridges and then to place this prepared clip surreptitiously in the possession of the unsuspecting firer. When the "dummy" finally enters the chamber of the piece and the man goes through the motions of firing, any flinching will be exposed, because there will be no recoil to obscure the convulsive muscular reactions of the firer.

The trick which has just been mentioned is quite effective as a temporary method of detection, at least the first time it is tried, but it cannot be repeated frequently. It is difficult to deceive a man who is at all alert more than once or twice. If a dummy cartridge be used and the firer be aware of its use, nothing will be accomplished, for he will not flinch. He must be tricked into believing that his piece is loaded with a ball cartridge and that he will be "kicked." Otherwise, the instructor might just as well require him

to simulate firing with an empty piece, which exercise belongs to an earlier stage of the 55 man's training.

Assuming that the dummy test must be used surreptitiously, it is considered, even so, that merely detecting and exposing flinching at widely separated times is not 60 the proper corrective measure. In the intervals, the man will continue to flinch. It is believed that exposure of flinching should be persisted in during a man's instruction practice until indications prove that he has 65 fully conquered the tendency.

Muscular control, which is necessary in order to fire properly, can only be regained by dogged perseverance in the exercise of will power. A flincher must force himself 70 to fire each shot carefully, and that is a hard thing to do in many cases. If he thinks that recoil will cover up his flinching and that no one will detect it, he is apt to give up all hope of making a good score and yield 75 to the tendency to flinch. Therefore, any scheme or device for indicating when a man flinches must be capable of exposing flinching each time it occurs in order to be successful.

It is the object of the present invention to get at the root of the trouble by providing a device which may be attached to the weapon used by a man suspected of flinching, or known definitely to be a flincher, and which will function each time he flinches. This will give the instructor and any of the firer's comrades present a tell-tale indication of flinching which cannot be denied by the firer. It then devolves upon the firer 90 to strengthen his own will power and regain muscular control, or be subjected to continual embarrassment.

An object in view also is to provide a device of this nature which is adapted to be 95 attached readily to a firearm without making any alterations in the construction of the latter. It is essentially a quickly attachable and detachable instrument for temporary use on any firearm.

A further object is to design a flinch indicator which is of extremely simple, unitary construction, which is composed of few parts, and which will be durable under service conditions.

Still further objects may appear as the

following specific description is read in connection with the accompanying drawings, in which:

Figure 1 is a side elevation of the device when attached to the United States magazine rifle, model 1903, showing the signal element in its exposed, operative position;

Figure 2 is a cross-sectional view taken on the plane indicated by line 2-2 of Figure 1, showing the signal element in retracted position; and

Figure 3 is a similar view on line 3-3 of Figure 1.

Before describing the mechanical details, it may be well to mention the manner in which it is intended to cause actuation of the indicator by flinching on the part of the firer. In seeking means for applying the power impulse represented by flinching to use as a prime mover for the indicator, the physiological reactions incident to flinching were considered, and from all of them one was selected as being preferable for the purpose. This reaction is the clenching of the fingers of the trigger hand.

While the inventive idea may be expressed in numerous ways, a convenient embodiment for use on the magazine rifle is represented in the drawing. It is to be understood that I do not want to be restricted to this particular embodiment of the invention alone. In adapting the device to the pistol and other weapons, or in meeting other requirements of practice, various changes may become necessary.

Referring to the drawings, the numeral 5 designates a signal element which is movably mounted and adapted to be shifted in position by a manipulating member 6. This manipulating member is preferably mounted adjacent to the "small of the stock" 7 of the rifle and is movable.

The signal element and manipulating member may be mounted upon the rifle in any convenient manner, but the construction shown should meet the requirements of practice. In this instance, both are supported by a spring clip 8, which includes breech-engaging portion 9 and guard-engaging portion 10. These clip portions are shaped to fit the breech and trigger-guard, respectively, and may be made of resilient sheet metal.

Pneumatic means for transmitting power impulses from the manipulating member to the signal element have been selected for reasons which should become obvious as the description progresses. Pneumatic means may be applied, as shown, by mounting a fluid cylinder 11 in a bracket 12 formed on clip portion 9, and fitting the signal element slidably in the cylinder as a piston. Element 5 should be striking in appearance so as to be readily distinguishable when exposed to view. This may be accomplished

by coating it with some paint or stain of contrasting color. The signal element should be cylindrical in form and adapted to work freely in the cylinder. Its length should be such that it will be entirely concealed within the cylinder in one extreme position, which may be termed its "inoperative position." By mounting the cylinder in such a position that it will be vertical when the rifle is horizontal, and by having the upper end of the cylinder open, the signal element will gravitate normally into inoperative position (see Figure 2) and may be caused to project from the cylinder into operative, indicating position, as shown in Figure 1.

The lower end of cylinder 11 may be connected with a compressible bulb 13 by means of flexible tube 14. By interposing the bulb between the manipulating member 6 and the small of the stock 7, movement of the member 6 toward the stock will cause deflation of the bulb and increase the full pressure in cylinder 11. The manipulating member is transversely bowed to confine the bulb and afford a grip which will fit those fingers of the firer's hand other than the trigger finger. The connection between the member 6 and the spring clip is in the form of a curved strip 15, which acts as a spring and normally maintains the members in the angular relation to the stock shown in Figure 1.

In order that gradual deflation of the bulb 13 will not cause actuation of the indicator by shifting signal element 5 upward, a small vent 16 may be provided in cylinder 11 near its lower end. Sudden deflation will thus be necessary in order to raise the pressure in the cylinder to a point in excess of that which can be dissipated quickly by escape of air through the vent.

The sensitiveness of the device may be regulated by varying the effective area of the vent 16. This is accomplished in the present instance by making the vent a longitudinal slot, and by fitting the lower end of the cylinder for sliding adjustment in a band 17 on bracket 12. Vertical adjustment of the cylinder will cause the band to mask varying lengths of the vent slot. A set screw 18 serves as convenient means for securing the cylinder in adjusted position.

A spring detent 19 is adapted to secure the signal element releasably in indicating position (Figure 1). It will do this automatically. The signal element may be reset readily by pressing it with the finger like a push-button.

The operation of the device when used on a rifle will now be described. Assuming that the firer is right handed, he will include the manipulating member 6 in the grasp of his right hand when holding the piece in firing position. The forefinger will be free to engage the trigger, but the other

fingers will bear against the manipulating member. When squeezing the trigger with the forefinger, involuntary articulation of the other fingers may occur. This will result in application of force to the manipulating member in the direction of the "small of the stock". The bulb 13 will thereby be compressed and the resulting increase in pressure of the confined air will be communicated to the interior of cylinder 11. If the finger pressure be gradual and slow, the signal element 5 will not be shifted into indicating position. However, should the firer "pull" the trigger violently, or flinch, the incidental clenching of all the fingers will cause rapid movement of the manipulating member and sudden increase in pressure within the cylinder. The signal element will thus be forced upward into the position of Figure 1, wherein it will be held exposed to view until reset.

It will be noticed that this device is capable of indicating convulsive "pulling" of the trigger as well as flinching.

25 I claim:

1. In a firearm accessory, a changeable indicating element, means responsive to the trigger-actuating operation of a firer for transmitting motion to the indicating element, and means adapted to cause a relatively permanent change in the indicating element upon the transmission of motion of predetermined velocity to the said element.

2. In a firearm accessory, a movable indicating element, means responsive to the trigger-actuating operation of a firer for transmitting motion to the indicating element, means for causing movement of the indicating element upon the transmission of motion thereto of predetermined velocity, and means for securing the indicating element in shifted position.

3. In a firearm accessory, a movable indicating element, means responsive to the trigger-actuating operation of a firer for transmitting motion to the indicating element, means for causing movement of the indicating element upon the transmission of motion of pre-determined velocity, and releasable means for securing the indicating element in shifted position.

4. In an indicator for firearms, a movable signal element, a movable actuating member responsive to nervous physiological reactions on the part of the firer, and means for transmitting motion from the actuating member to the signal element when the former has attained a predetermined speed of movement.

5. In an indicator for firearms, a movable

signal element, a movable actuating member responsive to nervous physiological reactions on the part of the firer, pneumatic means for transmitting motion from the actuating member to the signal element, and means for allowing limited relative motion between actuating member and signal element.

6. In an indicator for firearms, a movable signal element, fluid-pressure means for shifting the signal element, means for dissipating the fluid pressure within a predetermined range, and means responsive to nervous physiological reactions on the part of the firer for varying the fluid pressure through a greater range.

7. In an indicator for firearms, a movable signal element, fluid-pressure means for shifting the signal element, means for dissipating the fluid pressure within a predetermined range, means for varying the said range, and means responsive to nervous physiological reactions on the part of the firer for varying the fluid pressure through a greater range.

8. In an indicator for firearms, a fluid cylinder, a movable signal element having a piston working in the cylinder, and means responsive to nervous physiological reactions on the part of the firer for varying the fluid pressure in the cylinder.

9. In an indicator for firearms, a fluid cylinder having a vent to the atmosphere of sufficient cross-sectional area to dissipate the fluid pressure throughout a predetermined range, a piston working in the cylinder, a movable signal element adapted to be actuated by the piston, and means responsive to nervous physiological reactions on the part of the firer for varying the fluid pressure in the cylinder.

10. In an indicator for firearms, a fluid cylinder having a vent to the atmosphere, means for varying the effective cross-sectional area of the vent, a piston working in the cylinder, a movable signal element adapted to be actuated by the piston, and means responsive to nervous physiological reactions on the part of the firer for varying the fluid pressure in the cylinder.

11. In an indicator for firearms, a movable signal element normally disposed in inoperative position, means responsive to nervous physiological reactions for shifting the signal element into operative position, and releasable means for securing the signal element in operative position.

In testimony whereof I affix my signature.

DUDLEY B. HOWARD.
